UNITED STATES PATENT OFFICE.

EDWARD C. HAVILAND, OF CHAPPAQUA, NEW YORK, ASSIGNOR TO VAN KANNEL REVOLVING DOOR COMPANY, OF NEW YORK, N. Y., A CORPORATION OF NEW JERSEY.

COLLAPSIBLE-CABLE LOCK.

1,185,313.

Specification of Letters Patent. Patented May 30, 1916.

Application filed August 27, 1913. Serial No. 786,988.

To all whom it may concern:

Be it known that I, EDWARD C. HAVILAND, a citizen of the United States, residing at Chappaqua, in the county of Westchester and State of New York, have invented certain new and useful Improvements in Collapsible-Cable Locks, of which the following is a specification.

This invention relates to improvements in revolving doors, and more particularly to a device for detachably holding the cables connecting the wings of that type of revolving door known as the automatic collapsible revolving door, or the type shown and described in Patent Number 836,843, granted to Theophilus Van Kannel and dated November 27, 1906, wherein the wings are so held apart that the whole structure may be revolved in ordinary use, but in which the wings may be automatically folded or collapsed in case of panic, or where it is desired to fold the wings in the center of the casement, or to fold the wings and place them to one side of the casement.

The object of the present invention is to provide a novel means for folding the detachable end of the several cables, in such a way that a cushioning effect is accomplished when the ordinary operating pressure is applied to the wings, that is to say, the wings may have a slight yielding movement short of that required to disengage the locking devices as would be desired in an emergency or in intentional folding or collapsing the wings and another object is to provide a means having the further function of tensioning or keeping taut the cables between the wings and a still further object is to so construct such device that after the movable parts of the device have moved a predetermined distance, the detachable end of the cable will be automatically released.

As I have stated, the invention about to be described is adapted to form a part of a door structure as shown in the Van Kannel patent above referred to, and just so much of such door construction as is necessary to show the general arrangement of wings and their folding possibilities will be shown herein as is necessary to give an intelligent idea of the present device, but since the invention resides particularly in the releasing

devices, the description in the main will be confined to such devices.

In the drawings Figure 1 is an elevation of a revolving door structure, the parts being in normal position; Fig. 2 is a top plan view; Fig. 3 is a plan view of the door supporting disk, with the doors collapsed and folded to one side thereof, only a portion of the wings being shown; Fig. 4 is a broken horizontal section of one of the wings, taken through one of the locking devices, it being understood that there are a plurality of such wings identical in construction; Fig. 5 is a plan view with one of the plates removed; Fig. 6 is a plan view of the plate which receives the detachable end of the cable; and Fig. 7 is a view of the opposite plate which receives and holds the permanent end of the cable.

Referring to the drawings, the numeral 1 designates the door wings which, when in normal position occupy positions at right angles relative to a central spindle 2, which spindle is suitably supported at the top and bottom of the casement, and with which the wings revolve. Rigidly secured to the spindle 2, near the upper end thereof is a supporting disk 3 having a channel 4 therein. This disk is duplicated near the bottom of the door structure. Keyed to the spindle, near the upper and lower ends thereof are pinions 5 whose teeth mesh with toothed segments 6 carried by the several wings of the door. Each wing is provided with a spring pressed stud 8 which runs into channels of the disks, whereby the wings are guided with relation to the central pivot when the wings are collapsed or folded, or brought to the position shown in Fig. 3, the channel is divided quarterly with sockets or depressions 9 for the reception of the ends of the studs, in which sockets or studs will rest, when the wings are in their pivoted or extended positions.

The numeral 10 will designate a plate constructed for the reception of the permanent end of the cable. Such a plate is secured to one side of each of the wings, and is provided with a slot 11 having a narrowed central portion 12 and two end enlargements 13 and 14, the enlargement 13 being adapted to receive the head 15 of the permanent

end of the cable in attaching the cable to the wing. After the head of the cable is inserted through the larger opening of the slot, it is passed through the central contracted 5 portion and finally in the enlargement 14, this enlargement of the slot being of such diameter as to prevent the head from pulling through.

The numeral 16 designates the opposite 10 plate such a plate being attached to each wing opposite the plate just described. This plate 16 is provided with an elongated slot 17 for the reception of the head or knob 18 of the detachable end of the cable 19 and for 15 the further reception of the projection 20 of the gripper 21, which is pivoted upon a fulcrum pin 22 between the side flanges 23 of a sliding frame 24. The frame 24 is provided with a cross piece 25 which carries a 20 threaded stem 26 upon which works an adjusting nut 27 whose inner face is engaged by the inner end of a spiral spring 28 which surrounds the stem as shown, and the other end of this spring abuts against a cross- 25 piece 29 integral with the plate 16, through which piece 29 extends a screw-threaded rod 30, which carries an adjusting nut 31. The outer end of the threaded rod enters a head 32 which abuts against the inner edge of 30 the cut-out or recess in the wing in which the plates are received. The opposite end of the plate 16 is provided with a cross-piece 33 through which passes one end of a screw-threaded rod 34, which rod like the rod 30, 35 carries an adjusting nut 35, and whose outer end is held in a head 36 which abuts against the inner edge of the cut-out or recess in the wing opposite the head 32, by which means, the whole device is clamped and adjusted in 40 the recess in the wing.

Reverting to the gripper 21, the numeral 37 designates a spring which is coiled around the fulcrum pin 22 with one end in engagement with the gripper 21, and the 45 other end resting upon the top of the cross-piece 25, so that a constant tendency is exerted to keep the gripper in the position shown in full lines in Fig. 4. The gripper carries a roller 38 which is adapted to engage the head 18 on the detachable end of the cable 19 and forces it against the abutment 39 formed on the wall of the sliding frame 24. This abutment is received in the slot 17 in the plate 16 and moves with the 55 frame. The outer end of the sliding frame is provided with an antifriction roller 40 which works against the inner face of the plate 16, thus reducing the friction of the moving parts and lessening the wear. Se- 60 cured between the flanges 23 of the sliding frame is an angle iron 41, which projects inwardly in the path of movement of the head or knob 17 of the detachable end of the cable, to limit the movement of the knob or head in inserting it through the recess 17

and between the rollers 38 and abutment 39. Under ordinary conditions, when the door is adjusted in operative position, that is to say, when the wings are braced apart and during the operation of the door under these 70 conditions, when force is applied to any one of the wings such as would be applied in operating the door, the wing will give slightly in response to this pressure, but not sufficiently to release the knob, the movement of 75 the sliding frame in such a case being slight, but in the event of a panic, when excessive force is applied to one or more of the wings, or when a force is applied to two or more of the wings, when it is desired to collapse 80 them for folding purposes, the frame will be forced toward the central spindle of the door until the projection 20 of the gripper 21 engages the end of the slot 42 of the plate 16, when the gripper will be tripped or 85 rocked upon its fulcrum pin 22, forcing the roller 38 out of engagement with the knob 18, thus releasing the cable after which the wings may be folded, it being obviously necessary only to detach the end of one of 90 the cables, when the others, being flexible, will be merely doubled up between the wings.

When it is desired to release the ties manually to fold the wings either for the purpose of making them extend to any one direction in the middle of the casement or door, or to fold them for the purpose of sliding the whole revolving structure to one side of the casement as is possible in doors 100 of this type now commonly in use, obviously it will only be necessary to force the pivoted gripper 20 by hand against spring 37 from the position shown in Fig. 4, when the knob on the tie will be released from between the roller 38 and the abutment 39, and obviously to reinsert the knob or head of the tie for reestablishing the radial position of the wings, it will only be necessary to force the gripper inward sufficiently to permit the head to pass, when, upon the release of the gripper, it will bring the roller 38 against the head of the tie, forcing it against the abutment 39 and locking it against the withdrawal under normal conditions.

Having thus described my invention, what I claim is:—

1. A revolving door having in combination, a number of foldable wings, a tie having one of its ends detachably-connected to one face of each wing, a slideable gripper and a slideable abutment for detachably-holding said end, and means for tripping the gripper to release the detachable end of the tie, when abnormal pressure is applied 125 to the wing.

2. In a revolving-door, a central spindle, a series of folding wings mounted upon the spindle, a tie having one end permanently secured to the face of one wing, a locking 130

device carried by the adjacent wing for detachably holding the opposite end of the tie, said device consisting of a spring-pressed 5 slideable gripper and a slideable abutment, and means for tripping the gripper to release the detachable end of the tie.

3. A revolving-door having in combination, a number of foldable wings mounted on a spindle, ties connecting the adjacent faces 10 of the wings, one end of each tie being permanently attached to one face of each wing and the other end detachably-connected to the opposite face of the adjacent wing, a spring-pressed, slideable frame carrying a 15 pivoted gripper and an abutment for holding the detachable end, and means for tripping the gripper to release said detachable end of the tie.

4. In a revolving door, in combination, 20 a number of foldable wings, ties connecting the wings, slideable fixtures carried by the wings and carrying a gripper and an abutment for holding one end of the tie, and

means for engaging the gripper when the fixture has reached in its sliding movement, 25 a predetermined point, to trip the gripper and release the tie.

5. In a revolving door in combination, a plurality of foldable wings, ties connecting the adjacent sides of the wings, a spring- 30 backed slideable fixture carried by each wing, and carrying a spring-pressed gripper and an abutment, adapted to grasp one end of the tie and hold the same in the normal rotary movement of the door, and 35 means for tripping the gripper when the slideable fixture has reached a predetermined point, to release the tie, substantially as and for the purpose set forth.

In testimony whereof I affix my signature 40 in presence of two witnesses.

EDWARD C. HAVILAND.
